LOCOMOTIVE DRAFT DUCT

Leland G. Plant, Washington, D. C.

Application August 1, 1938, Serial No. 222,566

7 Claims. (Cl. 104—52)

This is an invention in construction and arrangement of draft ducts, branching from the inlet of an induced-draft type fan mounted on an enginehouse roof, to draft-tight connections made automatically with smoke stacks of locomotives entering the house.

The object of this invention is to improve upon structural and functional features of locomotive drafting devices in which ducts are used to convey smoke and gasses from the locomotive stack to a power driven fan, capable of inducing a draft in the locomotive firebox, and discharging the products of combustion therefrom, outside the enginehouse.

The advantage of removing locomotive smoke and gas from an enginehouse thru closed ducts in draft-tight connection with the locomotive smoke stacks, instead of discharging these products of combustion thru open vents in the enginehouse roof, has long been appreciated. Induced draft fans have been provided for this purpose, both in the arrangement of a fan individually applied to each stack and of one fan connecting with a plurality of stacks thru a series of openings in a duct. Both of these arrangements are subject to objections which are effectively overcome by the present invention.

A draft duct leading from a series of locomotive stack connections to a single fan, must have an increasing cross-area approaching the fan. When such a system is being run to accommodate only a minority of the locomotives for which stack connections are provided, the equipment is oversize and inefficient for such service. Where an individual fan is provided for each locomotive position, the initial installation cost is disproportionately high in relation to the average service requirements. Fan units adapted to be moved from locomotive to locomotive, involve additional labor and depend upon having open vents in the enginehouse roof.

In this invention, one fan serves a plurality of locomotives, each thru an individual duct, properly dimensioned for most efficiently drafting a single locomotive. In a group of locomotives served by one fan, it provides for selectively directing the flow of gasses from any one stack, either to the fan, or directly to atmosphere thru an outlet above the enginehouse roof.

Where individual fans are provided on an enginehouse roof above each locomotive stack, the entire weight of each motor and fan mechanism has to be supported by the roof at a point approximately midway between the rows of supporting posts in the enginehouse structure. This

necessitates a heavier roof structure than would otherwise be required and in existing buildings, the roof has often to be reinforced substantially to carry such additional weight. In my arrangement, a fan for serving two or more adjacent tracks can be placed directly over the row of roof supporting posts between said tracks.

With mechanical drafting of locomotives in an enginehouse, it is desirable to have means for automatically connecting and disconnecting the draft duct, as a locomotive moves in and out of the enginehouse. It is also desirable to allow for movement of the stack a few feet forward or back, while work is being done on the locomotive, without disturbing its contact with the draft duct. My invention accomplishes this in a novel and effective manner. It employs the old device of a semi-spherical surface, seating upon the inner rim of the locomotive stack, combined with the new design of a yoke engaging the stack in a self-centering manner and counterweighted at such a leverage angle as to compel the semi-spherical surface to seat fully into the stack, as the locomotive moves forward under the duct.

Movement of the duct in contact with a stack, to accommodate movement of the locomotive is here provided for, as in older devices, by designing one section of the duct to telescope within another and suspending these sections from a pivot, so that the duct is free to swing radially and its lower section to move horizontally with the stack. In combination with this construction, I introduce a novel hatch construction for an enginehouse roof structure, thru which the duct is free to swing in an arc from the pivot above the roof. Without this innovation, it is necessary, as in previous constructions, to keep the pivot point below the roof and where the roof is low, in relation to the locomotive stack height, considerable expense is incurred for raising the roof structure around the suspended duct, to allow for its swinging thru an arc, sufficient to accommodate some movement of the locomotive without breaking its connection with the stack.

This invention provides a duct structure that can be built of cylindrical pipe sections, hence economically adapted to fabrication from non-corrodible material, such as Transite pipe. It is also adapted to an assembly in which the joints between sections can be made draft tight by fabric connectors of non-inflammable material, such as glass cloth. These features are not exclusively adapted to my structure, but I am the

first to propose and disclose their use in combination with a draft duct device for automatically contacting the stacks of locomotives as they move into an enginehouse.

5 In the drawing of this invention, Figure 1 shows a section of the enginehouse roof R, spanning two adjacent locomotive positions. The stacks K of locomotives L, are shown in these positions and post P, supporting said roof midway 10 between the locomotive positions. Figure 2 is a sectional view of said enginehouse, in a plane at right angles to the first figure, showing one of the locomotives L, with its stack at various positions K, K-1 and K-2, in contact with the 15 duct device of this invention. In these views, S represents structural steel members on roof R, for supporting the draft duct device and T is a rectangular opening in said roof surrounded by a horizontally topped coping. In these Figures 20 1 and 2, the numerals apply to principal parts of this draft device as follows:

1 Semi-spherical seating surface with oval opening, adapted to seat in locomotive stacks of various sized openings, and to rest at various angles upon said stacks, in draft-tight contact therewith.

2 Lower section of swinging draft pipe, attached to semi-spherical surface 1, and telescoping over the section above.

30 3 Fabric connector of non-inflammable material, affording a flexible, but draft-tight connection between section 2 and

35 4 Upper section of draft pipe, swinging from a pivot above the roof; open at top and telescoping into section 2 at its lower end.

5 Horizontal section of draft pipe, connecting into section 4, and branching transversely therefrom, along the axis upon which the swinging section is pivoted.

40 6 Damper at upper end of section 4, controlling its opening to atmosphere.

7 Damper in transverse branch from section 4, controlling its opening into section 5.

45 8 Interlocking lever between dampers 6 and 7, requiring closure of one damper while other is open.

9 Horizontal section of draft pipe, telescoping over transverse branch 5, from section 4, and extending therefrom to

50 10 Draft fan with its motor mounted above enginehouse roof, on supports S, and connecting thru separate branch sections, as above, each to one of a plurality of locomotive stacks. To improve efficiency of the fan, smoke and gases 55 drawn from locomotive stacks may be discharged to atmosphere thru a flared stack, constructed upon the principle of a venturi, as indicated in the drawing.

11 Levers, counterweight and connecting rods 60 from the trunnion of damper 7, into the enginehouse within reach from floor. The counterweight may be used to normally hold damper 7 open, except when pulled closed. The position of damper 6 is controlled, in relation to damper 65 7, by interlocking lever 8.

12 Trunnion upon which the swinging duct section 4, is pivoted on one side, opposite transverse branch section 5, which serves as trunnion support for said section on its other side.

70 13 Rollers mounted on supports S, above roof R, in position to cradle the trunnion 12 and section 5, as pivots for the swinging duct section 4, suspended therefrom.

14 Cover plate resting on coping of roof opening T. The swinging duct section 4, passes thru

a hole in plate 14, sized to permit radial movement of the duct in relation to said plate, which is of sufficient length to slide back and forth on said coping to accommodate various positions of the swinging duct 4, without uncovering the 5 opening T.

15 Fabric watershed, bound around the swinging duct section 4, and fastened down to the sliding cover plate 14, affording a flexible closure of the hole in plate 14, thru which section 4 10 swings.

16 Trunnions projecting from both sides of duct section 2.

17 Yoke pivoted to trunnion 16, with a loop curved below this pivot to engage the stack K, 15 of locomotive L. Extending in the other direction from said trunnion, this yoke has a rigid length, acting as a lever upon trunnion 16, with its contact upon stack K as the fulcrum, when attached to a counterweight cord, carried thru 20 pulleys to

18 Counterweight hanging alongside enginehouse post P. This counterweight is of sufficient weight to draw the swinging duct section 4, with its dependent section 2, and stack contact- 25 ing surface 1, up to an angle at which it will clear the locomotive stack K, when the yoke 17 is not in contact therewith.

As a locomotive L, moves into the positions indicated on Figure 2, the contact of its stack K, 30 with yoke 17, draws up the counterweight 18, and permits the draft duct sections to swing downward until the semi-spherical surface 1 first rests in sealing contact upon the inner rim of stack K, then, as the locomotive continues 35 to move forward, the pull of counterweight 18, upon the lever arm of yoke 17, tends to pitch the trunnion 16 forward so that for any angularity of the swinging duct sections and surface 1, within range of stack K, said surface will rest 40 upon said stack in full annular contact with its inner rim.

In the regular operation of this draft duct device, a locomotive to be drafted is moved into the enginehouse and as it approaches the position at which it is to be stationed, its stack draws the swinging duct into draft tight contact therewith, for any position occupied, wherein its stack is within a few feet of a vertical line thru the pivot point from which it is suspended. The fan 50 10, induces a draft upon the locomotive, when damper 6 is closed and damper 7 is opened, the fan being set in motion by a control switch located in the enginehouse.

If desired to have the fan exert its full induced 55 draft force upon another locomotive, with which it has draft duct connection, damper 6 may be opened and damper 7 closed. With the dampers in that position, this locomotive is independent of the induced draft fan and may be drafted by 60 its own blower nozzle, or held in any condition desired with its stack in open communication to the atmosphere above the enginehouse roof, but without many objectionable features associated with the customary open smoke vents in an enginehouse roof.

For this invention, I claim:

1. In an enginehouse, a draft fan, a fan suction duct having a communicating swinging duct section suspended from pivot bearings by which 70 it is supported above the enginehouse roof, an opening in said roof thru which said section can swing in an arc, a cover plate for said opening, a hole in said cover plate thru which said duct section can turn in an arc, said plate being free 75

to slide back and forth upon a coping surrounding said roof opening, as required to accommodate the swinging movement of the duct section passing thru said hole, without uncovering said roof opening; a telescoping duct extension upon the lower end of said swinging section and a semi-spherical stack contacting surface upon the lower end of said extension, adapted to rest at various angles upon the inner rim of a locomotive stack, in full annular contact therewith, and an opening in said surface so shaped that it will not be exposed above the rim of said stack, at any angle of the surface while in contact with a locomotive stack.

2. In an enginehouse, a draft fan, a fan suction duct having a communicating swinging duct section suspended from pivot bearings by which it is supported above the enginehouse roof, an opening in said roof thru which said section can swing in an arc, a slidable cover for said opening adapted to move with said duct section, a hole in said cover for the passage of said swinging duct section, and a telescoping duct extension upon the lower end of said swinging section, said extension being adapted at its lower end to establish an effectively draft-tight connection with a locomotive stack, automatically, as the locomotive approaches its parking position, and to automatically disconnect itself from said stack when the locomotive is moved from the enginehouse.

3. In an enginehouse or the like having a roof opening therein, a smoke jack extending through said roof opening, means above the roof opening for swingingly supporting the jack and a slidable cover for said roof opening having an opening for said jack, said cover being adapted to slide with said jack whenever the jack swings.

4. In an enginehouse, a swingingly supported smoke jack extending through an opening in

the roof of the enginehouse, said smoke jack including a pair of laterally extending trunnions near the top thereof, bearings for said trunnions located above the roof opening of said enginehouse, and a sliding cover for said roof opening, having an opening through which the jack projects, said cover being adapted to slide with the jack whenever the jack swings.

5. A smoke jack as set forth in claim 4, wherein one of the trunnions comprises a pipe connecting the jack with a draft fan.

6. In an enginehouse, a swingingly supported smoke jack extending through an opening in the roof of the enginehouse, said smoke jack including a pair of laterally extending trunnions near the top thereof, bearings for said trunnions located above the roof opening of said enginehouse, and a sliding cover for said roof opening, having an opening through which the jack projects, said cover being adapted to slide with the jack whenever the jack swings, said smoke jack including a pair of telescoping pipe members, and a joint connector for said telescoping members comprising a skirt of flexible non-inflammable draft tight material connected at its ends to the telescoping members.

7. In an enginehouse or the like having a roof opening therein, a smoke jack extending through said roof opening, means above the roof opening for swingingly supporting the jack and a slidable cover for said roof opening having an opening for said jack, said cover being adapted to slide with said jack whenever the jack swings, and means for flexibly connecting the cover to said jack comprising a fluid tight fabric skirt of non-inflammable material connected at one end to the jack and at the other end to the slid-able cover.
